E. W. BAILLY

SAFETY LOCK FOR WOOD HEEL TURNING MACHINES

Filed Oct. 29, 1924

Inventor,
Eugie W. Bailly,
by L. C. Hammann Atty.

UNITED STATES PATENT OFFICE.

EMILE W. BAILLY, OF HAVERHILL, MASSACHUSETTS.

SAFETY LOCK FOR WOOD-HEEL-TURNING MACHINES.

Application filed October 29, 1924. Serial No. 746,501.

To all whom it may concern:

Be it known that EMILE W. BAILLY, a citizen of the United States, and resident of Haverhill, in the county of Essex and State 5 of Massachusetts have invented an Improvement in Safety Locks for Wood-Heel-Turning Machines, of which the following is a specification.

This invention relates to that class of 10 wood heel turning machines, or machines for shaping the sides and back of the heel blank, in which the heel blank holder is swung horizontally in relation to a pair of rotary cutters, successively, a machine of this character 15 being illustrated in my prior Patent #1,472,625.

In these machines the jack, or heel blank holder, is mounted so that it has free longitudinal and lateral movements and also is 20 pivoted to swing vertically. It is also guided in its lateral, longitudinal and tilting movements by cams, the cam which controls the tilting movement in this type of machine being a somewhat elliptically shaped track 25 usually arranged in a position slightly inclined to the horizontal, and acting to support the jack at its outer end. In the machine of my said patent, this track is directly engaged by an inclined foot, which is adjusted 30 in inclination to vary the extent of tilting movement of the jack, and, in some other machines the inclination of the track itself is varied, as in Russ Patent #1,247,335. In all machines of this type it is 35 customary for the operator, when he has finished the operation on a blank, to move the jack to the middle position with relation to the cutters, and as far away from the cutters as possible, and then to remove 40 the blank which has been operated on and clamp another blank in the jack while the jack is in this position. As thus held, a slight inward pressure on the jack will act to move it horizontally, so as to carry its 45 blank holding end towards one or the other of the cutters and a slight lifting action on the outer end of the jack will have the same effect. As the operator holds the blank in 50 position in the jack with one hand and clamps it, while thus held, with the other, it has sometimes happened, from various causes, such as by the effort of clamping, or by reason of the operator being pushed, or by carelessness, that the jack is moved from

this position so as to move the hand of the 55 operator which is holding the blank into contact with one of the cutters, with consequent serious results.

The object of my invention is to provide 60 a means for locking the jack in the position 65 in which it is held while changing the blank, so that it cannot, while thus locked, be moved either horizontally, or vertically, and which will cause the jack to be locked automatically when it is moved to this position 70 and the operator removes his hand from the operating handle of the jack, and which will not interfere with the normal operation of the machine, or in any way reduce the speed of its production. Also to provide a locking 75 means which may be readily applied to all existing machines of the type above referred to, at a reasonable cost.

I accomplish these objects in the manner hereinabove described and as illustrated in 75 the accompanying drawings in which:

Fig. 1 is a plan view of a machine of the type above referred to, containing a preferred embodiment of my invention.

Fig. 2 is a central vertical section thereof 80 at line *x*—*x* of Fig. 1.

Fig. 3 is a detail sectional view of the locking device.

Figs. 4 and 5 are detail views of the middle portion of the track.

The type of heel turning machine illustrated, in connection with which a preferred embodiment of my invention is shown, is substantially the same as that illustrated in my said prior patent and comprises the pair 90 of cutters 2 and 4, rotatable about vertical axes in the frame 5, and the jack base 6 connected by a horizontal pivot to a bracket 8, which is in turn mounted on a vertical pivot in one end of a link 12, the opposite 95 end of which is mounted to swing horizontally about the vertical pivot 14, mounted in a bracket on the frame. The jack is provided with any suitable blank-clamping means 15, the base member of which is directly over the bracket 8, and with a handle 16 at its opposite end by means of which the jack is manipulated when the turning operation is performed. The jack is supported at its outer end by the somewhat 100 elliptically shaped track 26, which is fixed on the frame in an approximately horizontal position, in which its upper edge is 105

usually in a slightly inclined plane, and by a foot 30, which is pivoted at 32 to the bottom portion of the jack and rests directly on the edge of the track, the inclination at which the engaging face of the foot is held being varied by adjusting a hand screw 34.

According to my invention I provide a plate 36, which is secured by bolts 38 to the inner or back side of the track 26, at the middle thereof, the holes through which the bolts are passed being somewhat elongated to permit slight vertical adjustment thereof, and said plate is provided with an obliquely extending aperture 39, which is equi-distant from the cutters 2, 4. As in all, or nearly all positions of adjustment of plate 36, the aperture 39 therethrough will be partly located below the level of the upper edge of the track 26, a notch 40 is formed in said track in line with said aperture, when the plate is adjusted to its lowest position. A locking bolt 42 is mounted to slide longitudinally in the jack base at a downward inclination from front to rear of approximately 45°, said bolt extending through the handle portion of the base and through the foot 30, and being movable between a position in which its lower end is above the bearing face of said foot and a position in which it extends some distance beneath said face. Said bolt is actuated downwardly by means of a spring 44, which is arranged thereon between a shoulder 43, formed by reducing the diameter of the upper portion of the bolt, and a guiding plug 45 in the upper end of the hole in which the bolt 42 slides, and the reduced portion of said bolt is extended above the upper side of the base and is provided with a cross pin 46, at its upper end. A handle 47 is mounted on a pivot 48 in the handle portion of the jack, said handle having a forked end portion 49, which extends beyond its pivot at each side of the upper portion of the bolt 42 in position to engage the pin 46, so that, when the handle is depressed, the bolt 42 will be drawn upward from the full line position, to the dotted line position of Fig. 2, in which latter position the handle 47 will lie close to the handle 16 of the jack and the end of the bolt will be above the under side of the foot 30.

While performing the turning operation, the operator grasps the handles 16 and 47, and presses the handle 47 down on the handle 16, thereby moving the bolt 42 up to its inoperative position, so that the action of the foot 30 on the track 26 will not be interfered with, and the jack may be swung freely from side to side. When the operation is finished, the jack is moved to the middle position and drawn away from the cutters as far as possible, as shown in Fig. 1. The plate 36 is so arranged that when the jack is in this position, the bolt 42 will

be held in line with the opening 39 therein, and also the notch 40 in the track. Consequently, when the handle 47 is released, the bolt 42 will be forced downward by its spring, so that its lower end portion will pass through the notch 40 and aperture 39, as shown in Figs. 2 and 3, in which position the jack will be firmly locked against movement in all directions, so that it cannot be moved either sidewise or lengthwise, or 70 swung upward, preventing all possibility of movement of the jack while the operator is changing the blanks. After the fresh blank has been clamped in position, the operator again depresses the handle 47, as he grasps the handle 16, and unlocks the jack, so that it may be moved in the usual manner. If the handle 47 should be released shortly before the jack is moved to its middle position, the end of the bolt 42 will ride on the top of the track, or of the plate 36, until the jack is moved into position to be locked. The hole in the foot 30 through which the bolt passes is enlarged sufficiently to permit adjustment of the foot to the necessary extent and the plate aperture 39 is also sufficiently enlarged to permit the bolt to pass therethrough in all the angular positions in which the bolt may be held due to various positions of adjustment of the foot 30. It will be apparent that the construction is such that it may be readily applied to existing machines.

I claim—

1. In a wood heel turning machine, a 100 pair of cutters, a blank holder mounted for universal horizontal movement to present the blank to the cutters, a track arranged to support the holder and to vary the vertical angular position thereof as it is moved horizontally in operative relation with the cutters, and means for locking said holder to said track when in its middle position thereon and withdrawn from the cutters.

2. In a wood heel turning machine, a 110 pair of cutters, a blank holder mounted for lateral and longitudinal movements horizontally to present the blank to the cutters, a track arranged to support the front portion of the holder and hold it in different angular positions to the vertical as it is moved laterally, a manually controlled locking device on the holder, and means carried by the track arranged to be engaged by said locking device when said holder is in a middle position with relation to the cutters and withdrawn therefrom to lock the holder against movement towards the cutters.

3. In a wood heel turning machine, a 125 pair of cutters, a blank holder mounted for lateral and longitudinal movements horizontally to present the blank to the cutters, a track arranged to support the front portion of the holder and hold it in different 130

angular positions to the vertical as it is moved laterally, a locking bolt slidably mounted on said holder, means on the track having an aperture arranged to receive said bolt when the holder is in its middle position with relation to the cutters and withdrawn therefrom, to lock the holder against movement horizontally and vertically, and manually controlled means for moving said bolt to and from its locking position.

4. In a wood heel turning machine, a pair of cutters, a blank holder mounted for lateral and longitudinal movements horizontally to present the blank to the cutters, and having a handle at its outer end for controlling the movement thereof, a track arranged to support the holder and control its inclination with relation to the cutters, a locking bolt slidably mounted in said holder and spring actuated to its operative position, a handle adjacent the handle of the holder for holding the bolt in its inoperative position, means on the track at its middle portion having an aperture arranged to receive said bolt when the holder is in its middle position with relation to the cutters and withdrawn therefrom to lock said

holder against movement towards the cutters.

5. In a wood heel turning machine, a pair of cutters, a blank holder mounted for lateral and longitudinal movements horizontally to present the blank to the cutters, a horizontally disposed track arranged to support the front portion of the holder and hold it in different angular positions to the vertical as it is moved laterally, a locking bolt slidably mounted in the holder, in position to move obliquely downwardly and rearwardly, means on the track having a recess arranged to receive the lower end portion of the bolt, as it is moved downwardly when the holder is in its middle position and withdrawn from the cutters, to lock the holder against horizontal and vertical movement towards the cutters, manually operated means at the front end of the holder for lifting the bolt to unlock the holder, and actuating means for moving the bolt to locking position when released.

In testimony whereof, I have signed my name to this specification.

EMILE W. BAILLY.
